Henry B. Fernald of Portland, county of Cumberland and
State of Maine

Letters Patent

The schedule referred to in these Letters Patent, and making part
of the same, containing a description in the words of the said Henry
B. Fernald himself of his improvement in applying the rising and
falling of the tide and other waters to the propelling of machinery.

To all persons to whom these Presents shall come.

See it known, that I, Henry B. Fernald, of Portland in the county
of Cumberland and state of Maine, have invented a new and useful
discovery in applying the rising and falling of the tide and other waters
to the propelling of machinery, called: A new and useful discovery which
consists in applying the rising and falling of the tide and other waters
to the propelling of machinery. In the rising of the tide or water the
buoyancy of the water is taken advantage of by means of a buoy of
sufficient strength and dimensions, connected by a rope or chain pas-
sing from the buoy under a pulley at the bottom of the water with
a wheel which moves the machinery. In the falling of the tide or
water, the weight of the buoy filled with water by means of a stop-
cock or otherwise operates as a propelling power, being so connected by
another rope or chain to another wheel as to operate alternately with
the wheel above mentioned. The invention is such that any water, which
may be made to rise and fall by artificial means may be applied
as above described. What I specifically claim as my invention or dis-
covery is the principle of applying the rising and falling of the tide and
other water to the propelling machinery. In testimony, that the above
is a true specification of my said discovery or invention as above described
I have hereunto set my hand and seal the 10th day of June in the year of our
Lord One thousand Eight Hundred and thirty five
